UNITED STATES PATENT OFFICE.

LEE R. ABERNATHY, OF LEAD, SOUTH DAKOTA.

APPARATUS FOR THE DESTRUCTIVE DISTILLATION OF OIL SHALE.

Application filed December 1, 1924. Serial No. 753,249.

This invention relates to process and apparatus for distilling oil, gas or gases from oil shale, and it includes novel steps and features hereinafter described and claimed.

5 The process consists in distributing the powdered oil shale in the chamber of a retort and simultaneously heating the powdered or crushed oil shale in the retort by the use of superheated steam, and in drawing 10 the gases from the intermediate portion of the distributing chamber.

The apparatus includes a hopper provided at its bottom with a chute, which communicates with the interior of a chamber mounted 15 upon the retort. A combined distributor and gas dome is located in the chamber, and means are provided for drawing the gas from the upper portion of the said dome. Means are provided for injecting super- 20 heated steam into the shale in the retort, whereby the gas is separated from the shale and ascends into the gas dome. A conveyor is provided below the retort and is adapted to remove the exhausted shale from the apparatus.

In the accompanying drawing:

Figure 1 is a vertical sectional view of the apparatus for distilling gas from oil shale.

Figure 2 is a plan view of the means for 30 injecting the superheated steam into the oil shale.

Figure 3 is a perspective view of the injector used in the extractor.

The apparatus includes a hopper 1, which is adapted to hold the powdered oil shale. The hopper 1 is provided at its bottom with a chute 2. The lower end of the chute 2 communicates with the interior of chamber 4 mounted upon a retort body 5. Two

40 gratings of angle iron, indicated at 6, are disposed transversely across the retort 5 in spaced relation to each other. Two series of radially disposed pipe sections 7 are located in the intermediate portion of the retort 5

45 one series below each grating and the said pipe sections are provided with steam outlet openings 7'. Steam spraying nozzles 8 are located in the retort 5 depending from the upper pipe sections 7. A cone shaped

50 gas receiver 15 is provided at its center with a dome 14 and said dome is located under the lower end of the chute 2, and the gas receiver 15 is held spaced from the inner surfaces of the walls of the chamber 4. A

55 pipe 16 connects at one end with the dome 14 and at its other end with the casing of a

suction pump 17 adapted to be operated by a belt 18, in a usual manner. The pipe sections 7 and the nozzles 8 are connected with a steam line pipe 19, through which super- 60 heated steam may be supplied to the sections 7 and the nozzles 8. The pipe 19 is provided with a valve 20, which controls the passage of the steam through the said pipe. The said valve is connected with the grate 65 6, and the said grating serves as thermos- static means for controlling the valves and the passage of the steam through the pipe 19.

The process of distilling oil gas from the oil shale rock consists in subjecting the 70 crushed shale to the separating action of superheated steam, heated at temperature from 700° Fahrenheit to 950° Fahrenheit, whereby the oil gas is recovered without burning the same. The crushed shale is 75 placed in the hopper 1 and passed through the chute 2 by gravity. The oil shale passes over the gas receiver 15, which serves as a spreader or distributor for the oil shale, and enters the chamber and the retort at the same 80 time the superheated steam is passed into the retort through the pipe 19 and is injected into the powdered oil shale through the outlet openings of the pipe sections 7 and the nozzles 8. The steam being thus 85 intimately mingled with the oil shale separates the gases therefrom, and the gas in the form of vapor ascends and passes into the receiver 15 and under the hood 14. From the hood 14 the gas is drawn through the pipe 16 by 90 the suction pump 17. A conveyor 12 is located in the lower portion of the retort and receives the exhausted oil shale and carries the same out of the retort in the usual manner.

95 The upper grating 6 of angle iron protects the upper steam pipes 7 from the weight of the oil shale coming down through the upper portion of the retort from the expansion chamber. The nozzles 8 extend at 100 right angles from the upper pipes 7, and the lower extremities of the ends of the nozzles rest upon the lower angle iron structure 6, as best shown in Figure 3 of the drawing. This arrangement strengthens the 105 structure of the retort, and protects the outlet or distributing opening from the weight of the oil shale, which is moving down through the retort. Thus, it will be 110 seen that two means are provided for distributing the steam within the retort, and both of these means are protected by angle

iron structures against the weight of the oil shale. Therefore it will be seen that the steam may be injected into the oil shale in uniform and steady streams.

5. Having thus described my invention, what is claimed is:

An apparatus for the distillation of oil from oil shales comprising a retort, means for injecting superheated steam into the retort, a chamber mounted upon the retort, a cone-shaped gas collector located in the top

of the chamber and provided at its top with a dome, an outlet pipe connected with the dome, and a hopper mounted directly above the dome of the gas collector and spaced therefrom so that the oil shale may flow down onto the dome along the outer surface of the gas collector to be distributed in the chamber above the retort. 15

In testimony whereof I affix my signature. 20

LEE R. ABERNATHY.
